UNITED STATES PATENT OFFICE.

BENJAMIN HIRSCHHORN, OF NEW YORK, N. Y., ASSIGNOR TO MILLIE PATENT HOLDING CO. INC., OF NEW YORK, N. Y., A CORPORATION OF NEW YORK.

TEA CARTRIDGE.

Application filed October 26, 1923. Serial No. 670,656.

To all whom it may concern:

Be it known that I, BENJAMIN HIRSCHHORN, a citizen of the United States, and resident of the city of New York, in the county of Bronx and State of New York, have invented certain new and useful Improvements in Tea Cartridges, of which the following is a specification.

The present invention relates to improvements in tea-cartridges, that is to say to devices for percolating or extracting the flavor from tea-leaves or coffee.

One type of these cartridges, described in U. S. Letters Patent No. 1,310,796, granted to me on July 22, 1919, comprises a bag of textile fabric having its mouth drawn into folds, the mouth of the bag being closed by a metal strip, in the form of a ring, which engages and compresses the folds, in combination with a suspending string which is attached to the said bag by said strip. In making these cartridges obviously a bag must be formed from a piece of textile fabric on a sewing machine and ring forming machinery must be made use of.

The main object of the present invention is to provide a tea cartridge, in the production of which the sewing operation and the ring forming machinery is done away with, thereby greatly reducing the cost of manufacture.

Generally speaking, the method of making the improved cartridge consists in shaping a piece of fabric so as to form a bag like container, charging said container with tea-leaves or coffee, puckering the mouth of the container, and tying around the said mouth one end of a string so as to close the same, to the other end of said string being attached a handle.

One of the many possible embodiments of the invention is illustrated in the accompanying drawings, in which:

Figure 1 is an elevation of a cartridge constructed in accordance with the present invention; Fig. 2 is a plan view of a piece of fabric of which the container of the cartridge is formed; Fig. 3 is a central vertical section taken through an apparatus and fabric piece, showing one of the steps of the method in making the cartridge; Fig. 4 is a similar section showing a further step; Fig. 5 is a similar section showing a still further step; and Fig. 6 is a plan view

of the inner end of the tying string ready for application to the shaped bag.

In producing the cartridge, first a piece 10 of open-mesh textile fabric, preferably of square configuration, is cut from a strip 60 (Fig. 2). This fabric piece is placed upon a female die 11, having a cylindrical recess 12, the bottom 13 of which is, preferably, rounded. Above the die 11 and in registering position with the recess therein is slidably arranged, in guides not shown, a male die 14, in the form of a tubular plunger, through which tea-leaves or coffee, sufficient for a single brewing are inserted in the bag-shaped container, as will hereinafter appear. The fabric piece 10 being placed onto the die 11, the tubular plunger is forced downwards into the recess 12 in the die 11, carrying with it the fabric piece, thereby shaping the same and forming a container 15, as shown in Fig. 4 of the drawings. A quantity of tea-leaves or coffee 15' (Fig. 4), sufficient for a single brewing, is then inserted through the tubular plunger into the container, after which the said plunger is withdrawn. One end of a string 16 is then formed into a loop 17 (Fig. 6), preferably by a slip knot 18, and the said loop extended around the open mouth 19 of the container 15 (Fig. 5). By decreasing now the loop in size, the mouth of the bag is puckered, the decreased loop embracing the puckered mouth and securely closing the same, thereby preventing escape of the contents.

For the purpose of facilitating the handling of the cartridge, there is secured to the free end of the string 16 a handle 20, for instance, of cardboard.

In brewing tea or coffee with the improved device, the cartridge is taken hold of by its handle 20 and lowered into a pot, the free end of the string and handle being permitted to hang over the mouth of the pot, after which its cover is put in place. The cover holds thus the outer end of the string and handle ready for further operation. Into the pot is poured a suitable quantity of boiling water, either before or after the insertion of the cartridge. When sufficient essence has been extracted from the tea-leaves or coffee within the cartridge, the pot cover is removed and the cartridge withdrawn by grasping its handle.

It is obvious that, while herein a specific

- method has been described for making the improved cartridge, any other way may be employed without departing from the invention, which lies mainly in the provision of
- 5 a cartridge including a container of open-mesh textile fabric shaped to form a bag-like receptacle, around the puckered mouth of which is tied a string, the other end of which has secured to it a handle.
- 10 What I claim is:—
1. A device for extracting essence from tea-leaves or coffee, comprising a bag-like container die-shaped of a piece of open mesh textile fabric, the mouth of said container being drawn into folds, a string having one of its ends tied around the mouth portion of
  2. A device for extracting essence from tea-leaves or coffee, comprising a die-shaped seamless bag-like container, the mouth of said container being drawn into folds, a string having one of its ends tied around the mouth portion of said container so as 25 to close the same, and a handle attached to the other end of said string.

Signed at New York, in the county of New York, and State of New York, this 16th day of October, A. D. 1923.

BENJAMIN HIRSCHHORN.
